UNITED STATES PATENT OFFICE.

CHARLES W. DAVIS, OF TORRINGTON, CONNECTICUT, ASSIGNOR TO THE TORRINGTON COMPANY, OF TORRINGTON, CONNECTICUT, A CORPORATION OF CONNECTICUT.

VACUUM CLEANER.

Application filed February 21, 1922. Serial No. 538,332.

To all whom it may concern:

Be it known that I, CHARLES W. DAVIS, a citizen of the United States, residing at Torrington, in the county of Litchfield, 5 State of Connecticut, have invented certain new and useful Improvements in Vacuum Cleaners, of which the following is a description, reference being had to the accompanying drawing and to the figures of reference marked thereon.

My invention relates to improvements in the vacuum cleaner shown in the patent to Quist and Anderson, No. 1,258,811, dated March 12, 1918.

15 The objects of the invention are to improve the lower edges of the lips of the nozzle so that as the machine is moved back and forth over the floor-covering and the suction draws the covering upwardly against the nozzle and into the same a wave-like motion will be imparted to the covering and permit the air to pass intermittently through the covering and then over it in order to loosen any dirt that has become embedded 20 therein; also to provide a nozzle that may be readily removed from the motor casing to permit one of a different type to be attached; also to provide the motor casing with front ground wheels independent of 25 the suction nozzle but adapted to drive the rotary brush of the said nozzle; also to provide a novel mechanism for securing either nozzle to the motor casing; also to provide adjustable cranked bars across the mouth 30 of the floor-engaging nozzle; also to reverse the direction of the rotary brush and increase the speed thereof.

These objects I can accomplish by the construction shown in the accompanying drawings, in which—

Figure 1 is a central vertical longitudinal section through the improved vacuum cleaner;

Fig. 2 is a front view partly in section, the brush being omitted;

Fig. 3 is a plan open front portion of the casing, the nozzle being removed;

Fig. 4 is a front elevation of the main suction nozzle;

50 Fig. 5 is a detail sectional view of the mouth of the main suction nozzle to better show the adjustable nozzle wire or crank;

Fig. 6 is a detail sectional view showing the hose attaching nozzle in place on the wheeled suction casing, and

55

Fig. 7 is a detail section to better show the connection between the bow spring and the axle bar.

The fan and motor casing 1 is provided with the usual exhaust 2. The front of the 60 casing 1 is provided with a flat machined face 3 having a circular inlet opening 4 and centering pins 5, 6 above and below the opening.

An adjusting ground wheel 7 is mounted 65 at the rear of the motor end of casing 1, while two ground wheels 8, 8 are mounted on the end of an axle 9 slidably mounted at its ends in the depending slotted lugs 10, 10 of an axle carrying channel bar 11 70 provided at the rear of its central arched portion 12 with a vertically disposed attaching member 13 secured to the lower end of the front face of casing 1 by means of two screws 14 passing through two vertical slots 14'; the top straight edge 15 of this attaching member forming a seat or rest for the suction nozzle, to be presently described. An intermediate slot 14² receives a third centering pin 14³ below pin 6—vertical adjustment of the axle bar is thus provided for.

The lower end of the attaching member 13 is provided with two horizontal aligned apertures 16, 16 into which fit two rivets 85 18, 18 extending through the straight middle portion of a bowed spring 17, the ends of which spring project forwardly and are formed with open longitudinal slots 19, 19 which straddle flattened portions 20, 20 adjacent the ends of the axle 9. The axle 9 is thus held from turning and is at the same time pressed forwardly in the slotted bearings 10, 10 of the axle carrying bar 11.

A clamping shaft 21 provided at one end 95 with a handle 21' is mounted in yielding half-bearings 22, 22 formed in the upper ends of two superposed U-shaped bearing plates 23, 23 of spring material secured to the front face of the attaching member 13 100 by the same screws 14 that secure the channel bar 11 to the casing 1.

The bearing plates 23 project up through slots 24 in the channel bar 11, and the lower

edges of the plates 23 are recessed at 25 to avoid contact with the heads of the pins 18 on spring 17. The shaft 21 is offset or cranked between its ends as shown at 26 5 to form a cam-like clamping bar or eccentric to clamp the lower end of one of the nozzles to be presently described, against the front of casing 1; a turn button or the like 27 being pivoted at the upper portion of the 10 casing front to clamp the upper end of the nozzle to the casing front. So far as described, it will be seen that the motor or fan casing is free to be moved along the floor while resting on the front and rear 15 ground wheels regardless of which form of nozzle may be employed.

The main or wide floor engaging nozzle 30 is provided with a brush 31 as in the patent above referred to, and it also has 20 drive wheels 32 mounted in separate chambers 33 at the ends of the lower open end or mouth of the nozzle as in said patent. There is, however, a second or driven wheel 34 for each drive wheel 32, which driven 25 wheels 34 are rotated by contacting with the larger peripheries of the spring pressed ground wheels 8, 8. These driven wheels 34 cause the brush 31 to be driven at a much greater speed and also reverses the direction 30 of rotation of the brush 31 and cause it to sweep the dirt rearwardly into the path of the air current, and I find the result to be a great improvement. The rear side of the nozzle 30 has a central outlet neck terminating in a flat vertical attaching plate 35, machined to closely fit the similar face at the front of the casing 1. The upper and lower 35 edges of the plate or flange 35 have open slots 36, 37 to receive the pins 5 and 6, respectively, and the lower horizontal edge 38' of the flange 35 rests upon the straight edge 15 of the bar 11 directly behind the crank 26 so that when the crank 26 is moved by the handle 21 against the lower side of 40 the flange or plate 35, and the turn button or latch 27 is turned into engagement with the upper recessed end of the plate or flange 35, the nozzle will be held in airtight engagement with the suction side of casing 1. 45 The longitudinal edges of the lower open end of the nozzle 30 are curved on arcs of a circle as at 38 and 39, beginning about a half inch from each end and the height of the arc 38 on the front lip or edge of the 50 nozzle is slightly greater than that on the rear lip 39. The object in thus forming the lower edges of the nozzle lips is as follows:— When the cleaner is moved over a rug, carpet or other floor-covering, the suction pulls 55 the floor-covering away from the floor and holds it close against the lower end of the nozzle. It also draws the floor-covering up into the nozzle between the front and rear edges. As the brush revolves it tends to 60 push the carpet or the like away from the 65

nozzle, thus allowing the entering air current created by the fan to flow over the carpet. This is repeated continuously as the cleaner is moved back and forth with the result that the rug or carpet will be constantly worked up and down and the air will be intermittently drawn therethrough and then over it. The wave-like action of the rug or carpet tends to loosen any dirt that has become embedded in the same, so a better cleaning results than would be the case where the lower edges of the nozzle lips are straight.

In order to regulate the upward movement of the carpet or the like into the nozzle, two or more transverse cranked nozzle bars or rods 45, 45 are journaled at their ends in bearings 46, 46, in the lower portions of the front and rear lips or walls of the nozzle below the brush.

The rear straight ends 47, 47 of these cranks extend through the rear wall of the nozzle when they are threaded and provided with clamp nuts 48, 48 by means of which the cranked portions may be adjusted toward and from the material being cleaned and so limit the distance the material may be sucked upwardly into the nozzle toward the brush, said ends 47 having collars 49, 49 at the inner ends of their bearings against which the collars are drawn by the clamping nuts 48.

In order that a hose and attachments (not shown) may be employed, a second nozzle 50 is employed, this nozzle having an attaching flange 51 which is the counterpart of that on the main or floor engaging nozzle. With this nozzle 50 in place, the cleaner may be moved from place to place as the casing has the front and rear ground wheels attached thereto no matter which nozzle may be employed.

When the main nozzle is clamped in position, its brush driving wheels 34 will be brought into contact with the ground wheels 8, 8 so that the brush will be rapidly rotated to the rear. This has proved to be a highly valuable feature as it allows of the employment of a brush in the type of machine having movable and interchangeable nozzles, and front ground wheels on the fan casing.

Various modifications may be made without departing from the spirit of my invention.

The motor and fan may be of any suitable construction and form no part of my present invention.

Having thus described the invention, what I claim as new and desire to secure by Letters-Patent, is:—

1. A vacuum cleaner comprising a main suction casing having an inlet at its front, a motor driven pump, interchangeable floor and hose nozzles adapted to be secured in

- registry with said inlet, ground wheels carried by the front end of the main casing, a rotary brush mounted in the mouth of the floor nozzle and provided with drive wheels 5 adapted to be driven from said ground wheels when the floor nozzle is in place and the ground wheels serving to support the suction casing when the floor nozzle is removed and the hose nozzle is in place.
- 10 2. In a vacuum cleaner, the combination with a main suction casing having ground wheels supported thereby, of a suction nozzle having a rotary brush; a plurality of axially rotatable cranked nozzle bars extending transversely across the mouth of the nozzle below the brush, and means for adjusting the cranks individually toward and from the brush and mouth of the nozzle.
- 15 3. In a vacuum cleaner, the combination with a main suction casing having ground wheels supported thereby, of a suction nozzle; transverse nozzle bars journaled at their ends to rotate in the mouth of the nozzle, cranked between their ends within the mouth of the nozzle and threaded at their rear ends to hold the rods in their adjusted positions, and clamping nuts on said threaded ends.
- 20 4. In a vacuum cleaner, a suction casing having a flat front provided with an inlet opening, a transverse shaft journaled on the casing below said opening and offset between its ends to form a cam-like flange-engaging clamp, and a second flange-engaging clamping means above the said opening whereby nozzles having like attaching flanges may be removably secured to said casing.
- 25 5. In a vacuum cleaner, a suction casing having a flat front face provided with an inlet opening, a transverse shaft below said opening, yielding bearings on the casing for said shaft; the shaft being offset between the bearings to form a cam-like flange-engaging clamp, and a second clamping member on said front face above the inlet opening.
- 30 6. In a vacuum cleaner, a suction casing having a flat front face provided with an inlet opening, upper and lower nozzle clamping devices on said front face, a transverse axle bar secured at its middle to the lower portion of said front face, and having slotted ears at its ends, an axle mounted at its ends in said bearing slots, ground wheels on the outer ends of the axle, a bowed spring secured at its middle to the middle of the axle bar and forked at its ends to straddle the axle and press it forwardly; the axle and said forked ends being shaped to prevent rotation of the axle.
- 35 7. In a vacuum cleaner, a suction casing having a flat front face, and an inlet opening, a removable flanged nozzle to register with said inlet opening, an axle bar bolted between its ends to the lower portion of said front face, and having slotted bearings at
- its ends, an axle mounted in said bearings, a bowed spring removably engaged between its ends with the outer face of the axle bar, and at its ends engaging the axle to press it forwardly, bearing plates at the outer side 70 of the spring, a single set of screws securing the bearing plates, spring and axle bar to the front face of the casing; the upper ends of the bearing plates being formed with bearings, a clamp shaft journaled in said 75 bearings and offset between its ends to receive and bind a nozzle flange against the front face of the casing, and a second upper clamping device above the inlet opening.
8. In a vacuum cleaner, the combination with a suction casing having an inlet opening, a nozzle having a flange engaging the casing around its inlet opening, a shaft having a cam forming portion to force the nozzle flange firmly against the suction casing, yielding bearings for said shaft to force it towards the suction casing, and a second clamping means on the suction casing and engaging the nozzle flange at a different point from that engaged by the offset shaft. 80
9. In a vacuum cleaner, the combination with a suction casing having a flat front face provided with an inlet opening and centering pins above and below said opening, a pivoted turn button above the opening, and a cam forming clamping shaft below said opening, of a nozzle having an attaching flange adapted to be clamped to the said front face by said clamping devices and provided with recesses to engage the said centering pins. 85
10. In a vacuum cleaner, the combination with the suction casing provided at its front with an inlet opening and flange engaging clamping devices, an axle bar secured between the ends to the lower portion of said suction casing, and having slotted bearings at its ends, an axle mounted in said slotted bearings and having flattened portions, ground wheels on the ends of the axle, spring arms pressing the axle forwardly and having forked ends embracing the flattened portions thereof, of a suction nozzle flanged at its inner end for clamping engagement by said clamping devices and provided with a rotary brush in its mouth and driven from said ground wheels. 90
11. In a vacuum cleaner, the combination with the suction casing provided with a front inlet opening, a removable suction nozzle registering with said inlet opening, a rotary brush mounted in the mouth of said suction nozzle and drive wheels at the ends of the shaft, of an axle bar secured to the front of the casing below and independent of the suction nozzle, an axle mounted in the ends of the axle bar and having flattened portions near its ends, ground wheels on the axle ends and engaging the brush driving wheels, and a plate spring secured between 115
- 120
- 125
- 130

its ends to the axle bar and having forked ends engaging the flattened portions of the axle to prevent its turning; said spring yielding rearwardly when the nozzle is applied to the casing with its brush actuating wheels engaging said ground wheel.

12. In a vacuum cleaner, the combination with a main suction casing, of a suction nozzle

formed of rigid material and having its lower edges curved on arcs of circles 38, 39, ¹⁰ the height of the arc 38 on the front edge being greater than that on the rear edge.

In testimony whereof, I affix my signature.

CHARLES W. DAVIS.
